Patented Sept. 7, 1971

221,725

COMBINED PIN CUSHION AND BANK

Grace R. Tatum, M. R. Reesers Summit,
New Cumberland, Pa. 17070

Filed Apr. 14, 1969, Ser. No. 16,757

Term of patent 3½ years

Int. Cl. D6—99

U.S. Cl. D3—19

FIG. 1 is a perspective view of a combined pin cushion and bank showing my new design, the side opposite that shown is substantially similar thereto;

FIG. 2 is a cross sectional view thereof; and
FIG. 3 is an exploded view of the design.

I claim:

The ornamental design for a combined pin cushion and bank, as shown and described.
